UNITED STATES PATENT OFFICE.

AUGUST F. BANKE, OF PILOT POINT, TEXAS.

ICE-BLOCK-SCORING MACHINE.

Application filed September 29, 1923. Serial No. 665,678.

This invention relates to ice block scoring machines, and particularly to novel means for scoring the block vertically on its longitudinal edge to divide the block into 5 three sections of approximately one hundred pounds each, when blocks of the conventional size are treated, and thereafter scoring the said block longitudinally to divide the block into what would be twenty-five 10 pound sections while it is passing through the machine, there being means for intermittently moving the block to deliver it to the first named scoring mechanism, and thereafter the block is continuously moved 15 while being scored longitudinally.

It is a further object of this invention to provide a novel machine which will automatically shift the mechanism to impart the intermittent movements in order that attendance of an operator will be unnecessary 20 during the time the machine is running. By reason of the foregoing facts, the cost of scoring blocks will be comparatively small, and the machinery necessary for effecting the result is comparatively inexpensive and is of durable construction.

A still further object of this invention is to produce a machine which will score the blocks when on their edges as they come 30 from the freezing cans, thus making it unnecessary to shift the positions of the blocks to present them to the operative parts of the machine.

It is a further object of this invention to produce a machine of the character indicated in which the conveyer receives the block and intermittently transfers it from one end of the machine to the other, discharging the block in its scored state for distribution.

It has been found that a machine made in accordance with this invention will treat the blocks about as rapidly as they can be discharged from the cans, and the capacity 45 of one machine has been as high as one and one-fifth tons of ice per minute.

With the foregoing and other objects in view, the invention consists in the details of construction, and in the arrangement and combination of parts to be hereinafter more fully set forth and claimed.

In describing the invention in detail, reference will be had to the accompanying drawings forming part of this application 55 wherein like characters denote corresponding parts in the several views and in which—

Figure 1 illustrates a view in elevation of an ice scoring machine embodying the invention, the view being broken away longitudinally;

Figure 2 illustrates a top plan view thereof;

Figure 3 illustrates a sectional view on the line 3—3 of Fig. 1;

Figure 4 illustrates a sectional view on the line 4—4 of Fig. 1 and Figure 5 illustrates a detail sectional view of trip mechanism whereby the saws on horizontal shafts are released to be positioned out of contact with a cake of ice when they have concluded the scoring of said cake.

In these drawings, 10 denotes a suitable rectangular frame properly braced to produce such strength as may be necessary to withstand strain incident to the use thereof, 75 and preferably the frame supports a motor 11, which motor may be of any appropriate type, that is to say, it may be an electric motor or a gasoline motor, or, if necessary, power can be communicated to the machine by belting from a remote source, although preferably, the self-contained machine will be found more satisfactory as it may be moved from place to place without reference to the source of power.

A conveyer 12 is stationed in an inclined position at the receiving end of the frame and it is designed to receive blocks and carry them into the frame to the main conveyer 13 which travels the full length of the frame. 90 The conveyer is preferably of a type having spurs 14 which will impinge the ice and prevent it from being dislodged while traveling through the frame.

On each side of the frame near the receiving end, guides 15 stand vertically and sleeves 16 are slidable on the said guides. The sleeves are formed to produce bearings for the shaft 17, which shaft is rotatably mounted in the bearings and constitutes supports for the scorers 18 which are in the nature of saws. The scorers are spaced apart a distance equal to one-third of the length of the block being treated, as it is the purpose of the inventor that the block shall be carried into the frame until it is in position to be operated on by the scorers 18 when the sleeves are moved vertically on the guides. The sleeves are connected by a yoke 19 to which a link 20 is connected, and the said link has its upper end connected to a crank 21 of the crank shaft 22, the said

2
crank shaft being rotatably mounted in suitable bearings 23 on the frame.

In describing the gearing, reference will be made to it as consisting of sprocket chains and sprocket wheels, but it is to be understood that this term is used analogously with belts and pulleys, and the inventor does not wish to be limited with respect to the means for transmitting the power.

10 A sprocket wheel 24 is secured to the shaft 22 and a sprocket chain 25 operates thereover from a sprocket wheel 26 on the shaft 27. The sprocket wheel 26 is integral with a clutch member 26^a on the shaft 27. The shaft 27 has a clutch member 28 that is splined thereon which coacts with the clutch members 26^a and 29. The shaft 27 is driven by a sprocket wheel 30 which is engaged by a sprocket chain 31 driven from the shaft 32 through the medium of the sprocket wheel 33. The shaft 32 is connected to the motor 11 through the sprocket chain 34 and sprocket wheels 35 and 36, the former of which is secured on the shaft 32 and the latter of which is secured on the drive shaft of the motor.

15 The clutch member 29 drives a sprocket wheel 37 and this sprocket wheel is connected to a sprocket wheel 38 on the shaft 39, and the said shaft 39 operates the conveyer 13 to which reference has been made. A sprocket chain 40 engages the sprocket wheels 37 and 38, as shown in Fig. 1.

20 The clutch member 28 is engaged by a lever 41 which serves to move it axially of the shaft into and out of engagement with the clutch members 26^a and 29 alternately, and this lever 41 is actuated by a shaft 42 rotatable in a bearing 43 at the side of the frame. The shaft has a finger 44 which is in the path of travel of a cam 45 carried by one of the sleeves 16 in order that when the sleeve has reached a predetermined height, it will communicate motion to the shaft and 25 it will in turn disconnect the clutch members and disconnect the drive which operates the vertically movable scorers. It will be seen that when the clutch members are in engagement and the motor is running, the shaft 22 will be rotated, thus causing the cranks to lift the vertical scorers and this motion will continue until the clutch is thrown out of operative position.

25 The arrangement of the clutch member 28 is such that it is alternately thrown into engagement with the clutch member 26^a and the clutch member 29. When the clutch member 28 is in engagement with the clutch member 29, the scorers 18 will be arrested and the conveyer 13 will be operated to carry a cake of ice away from the scorers and to deliver another cake of ice to the scorers.

30 The shaft 42 is rotatable as stated and it has an arm *a* rotatable on it. There is a collar *b* secured on the said shaft and it has

a shoulder *c* that is engaged by a dog *d* and the said dog is pivotally mounted on the arm *a*. The dog is in the shape of a bell crank lever and one arm *e* thereof is adapted to travel into engagement with a trip *f* which will force the dog out of engagement with the shoulder and release the shaft in order that it will turn in one direction under the action of the spring *g* which has one end anchored to a stationary object *h* and the other end connected to an arm *i* extending from the shaft 42, so that when the dog is disengaged from the shoulder of the collar, the shaft will rotate independently of the arm *a* to return the arm to a position to shift the clutch members.

35 The arm *a* is returned to its normal position by the spring *j* having one end anchored to the collar and the other end connected to a pin *k* on the hub of the arm. The dog is held in operative position by a spring *m*, the action of which will be apparent from an inspection of Figure 5.

40 The arm *a* is intended to extend into the path of travel of the cake of ice that is being moved by the conveyer and the relation of parts is such that when the cake of ice has reached a predetermined station or location with respect to the scoring saws 18, the clutches will be shifted to disconnect power from the conveyer to connect power to the scorer-operating devices so that the scorers will be moved vertically of the frame. When the scorers have completed a cycle of 45 operation they again shift the clutches through the medium of the cam 45 which engagess the arm 44 to partially turn the said shaft and the conveyer then carries the cake of ice out of engagement with the arm *a* and it returns to its normal position in the path of travel of the next succeeding cake of ice and a repetition of the operation again takes place. At the completion of the downward stroke of the frame carrying the scarfing saws 18, the frame and saws will be moved upward adjacent to the top of the frame and will be held in such position by the cam 45 which is maintained in an elevated position by the arm 44 on shaft 42. When in this position, the vertical saws 18 will be above the cake of ice. The movement imparted to the arm 44 will turn the vertical shaft 42 so that the carrier belt upon which a block of ice rests will start its movement to carry the cake of ice toward the scarfing saws 53, and as soon as the cake of ice has passed the projection *a*, the clutch will be thrown by reason of springs so that drive chain 31 will actuate the saws 53.

45 The shafts 17, one of which is provided on each side of the machine, are operated in identical manner, and the description of the means for operating one shaft will suffice as an understanding of the invention in this respect.

A telescopic shaft 46 is provided on each end of the machine and one end is connected to a shaft 17 by a universal joint 47, whereas the other end is connected by a universal joint 48 to a stub shaft 49 which rotates in suitable bearings in one of the frame members, the said stub shaft being supplied with a beveled gear wheel 50.

A shaft 51 is journaled vertically in the frame and it has a beveled gear wheel 52 which meshes with the gear wheel 50 so that when the shaft 51 is driven, motion will be communicated to the vertical scoring shaft 17. The shaft 51 has scores 53 in the nature of saws secured to it in spaced relation to each other, and as the blocks of ice are carried by the conveyer to the discharge end of the frame, these scorers produce slots in the blocks which extend longitudinally 20 of the said blocks.

The upper end of each of the shafts 51 has a gear wheel 54 which meshes with a gear wheel 55 on the shaft 32, which shaft is driven as heretofore described, so that 25 when the motor is started, the scores are rotated continuously during the operation of the motor.

I claim:

1. In a scoring machine for cakes of ice, a frame, a conveyer operatively arranged in the frame to travel longitudinally thereof, vertically movable scorers in proximity to the front end of the frame, means for moving the scorers vertically, means for rotating the scorers, means for communicating power to the scorer moving means, means for communicating power to the conveyer, and means automatically shifted when the scorers are elevated for transferring power 40 from the scorers to the conveyer, substantially as described.

2. In a scoring machine for blocks of ice, a frame, a conveyer operatively arranged in the frame to travel longitudinally thereof, vertically movable scorers in proximity to the front end of the frame, means for moving the scorers vertically, means for rotating the scorers, means for communicating power to the scorer moving means, means for communicating power to the conveyer, automatic means for intermittently withdrawing power from said conveyer, means shifting when the vertically movable scorers are elevated and for transferring power to the conveyer, and a plurality of horizontally rotatable scorers adapted to operate on blocks of ice while moving with the conveyer.

3. In a scoring machine for blocks of ice, a frame, a conveyer mounted to operate 60 therein, an extension conveyer for delivering blocks of ice to the main conveyer, vertically movable scorers, means for intermittently moving the conveyer and operating after the completion of vertical scorers in the 65 sides of the cake of ice, and after such scoring means for intermittently moving the vertically movable scorers, and means for shifting power alternately from the scorer elevating means to the conveyer driving 70 means.

4. In a block scoring machine, a frame, a conveyer mounted to operate to deliver a block of ice between the frame, a conveyer for delivering blocks of ice to position below, vertically movable scorers, means for intermittently moving the second conveyer, means for intermittently moving the vertically movable scorers, means for shifting power alternately from the scorer elevating 80 means to the conveyer driving means, and horizontally rotatable scorers in the path of travel of the blocks of ice carried by the second conveyer.

5. In an ice scorer, a frame, conveyers 85 therein, vertical guides, sleeves on the said guides having bearings, a vertically movable and intermittently rotatable shaft rotatable in the bearings, scorers on the said shaft, means for moving the sleeves vertically, 90 means for applying power to the sleeve moving means, means for intermittently driving the conveyer means for automatically applying power to the said scorers and after scoring to the conveyers, and 95 means for scoring the blocks longitudinally when moving with the conveyers.

6. In an ice scoring machine, a frame having conveyers upon which cakes of ice are delivered, longitudinal shafts having thereon vertically disposed saws, sleeves associated with the shafts and in slidably engagement with guides, means for moving the shaft, having the scoring saws thereon vertically, automatic means for disconnecting 100 the conveyers while the scoring saws are in engagement with a cake of ice which is being scored vertically thereby, means operatively connected with the carrying means for said saws for elevating the same upon 105 the completion of their work and after such elevation to maintain them in a raised position, and automatic means for actuating the conveyer belts to carry the vertically scored cake of ice to horizontally scoring saws.

AUGUST F. BANKE.
